UNITED STATES PATENT OFFICE.

CHARLES SCHLAYER, OF NEW YORK, N. Y., ASSIGNOR TO CHARLES W. JACOB, OF NEW YORK, N. Y.

AUXILIARY GASEOUS-FUEL MIXER.

1,178,540.

Specification of Letters Patent. Patented Apr. 11, 1916.

Application filed March 18, 1914. Serial No. 825,460.

To all whom it may concern:

Be it known that I, CHARLES SCHLAYER, a citizen of the United States, residing in the borough of Manhattan, in the city, county, and State of New York, have invented certain new and useful Improvements in Auxiliary Gaseous-Fuel Mixers, of which the following is a specification, reference being had therein to the accompanying drawings, which form a part thereof.

My invention relates to an auxiliary gaseous fuel mixer and more particularly to an appliance adapted to be disposed in the path of the mixture flowing from the carbureter to the engine cylinder to secure a more thorough admixture of the vaporized hydrocarbon and air, or other constituents of the explosive mixture. In this art a device adapted to be rotated under the flow of the explosive mixture has been used with highly satisfactory results, securing higher engine efficiency from a given quantity of hydrocarbon, or the same engine efficiency with the spray nozzle throttled down to a considerable extent. In my experiments with a mixer of the type immediately above referred to, I have discovered, however, that the intermittent action of the engine impulses is such as to prevent uniformity in the action of such a device, or to bring the device up to a maximum speed with sufficient rapidity to secure the best results.

By my present invention I am enabled to produce an auxiliary gaseous fuel mixer wherein the rotary agitator will intercept substantially all of the explosive mixture flowing from the carbureter to the engine cylinder or cylinders without obstructing the manifold, the carbureter offtake port or the engine intake ports, in a manner to materially affect the action of the carbureter and at the same time, insure the rotation of said agitator at substantially its maximum speed during substantially the entire intake or suction stroke of an engine cylinder. A mixer made in accordance with my invention is also so constructed as to avoid a possible displacement of the supplemental driving means for the agitator with the two-fold result that the agitator itself is held rigidly, and any globules of hydrocarbon passing adjacent the axis of the agitator will be projected outwardly and within the range of the operative portions of the agitator and radially of the pipe, through

the volume of the explosive mixer, and against the sides of the pipe in a manner to thoroughly disrupt the same. I also unite the succeeding sections of the agitators in a manner to hold them firmly with relation to the supplemental vanes, the connecting means being so disposed as to assist materially in agitating the explosive mixture, thus contributing toward the efficiency of the mixer.

A device made in accordance with my invention may be and preferably is, so constructed as to form a slightly constricted passageway adjacent the intake of the mixer, and extending to a point of the agitator at approximately the greatest diameter thereof, thus bringing the entire flow of gas within the operative range of the agitator, directing it upon the supplemental starting device and permitting it to expand or change its direction of flow while still within operative range of a portion of the agitator.

By a construction such as that immediately above referred to the mixer is not only adapted to be mounted in the manifold adjacent to the carbureter but may be mounted directly in the cylinder ports leading to the engine intake valves.

The invention consists in the novel features of construction and combination of parts hereinafter set forth and described and more particularly pointed out in the claims hereto appended.

Referring to the drawings: Figure 1 is a diagrammatic showing of a four-cylinder engine manifold with my mixer applied to the manifold at the carbureter and also at the intake port of each of the engine cylinders; Fig. 2 is a side elevation of a mixer embodying my invention; Fig. 3 is a detailed view of the agitator and the supplemental vanes carried thereby; Fig. 4 is a vertical section through the agitator showing the supplemental vanes in elevation, and Fig. 5 is a plan view of the said vanes detached from the agitator.

Like letters refer to like parts throughout the several views.

In the accompanying drawings the engine cylinders are indicated at 1, 2, 3 and 4, said cylinders respectively having an intake port a' , a'' , a''' , a'''' which intake ports are in communication with different leads of the manifold b . At c I have shown a carbureter of

ordinary construction, the offtake of which is in communication with the trunk of the manifold *b*. In the drawings the manifold is broken away to disclose the improved mixer. Inasmuch as each of the mixers shown in connection with the engine is substantially like every other, a description of but one of them will be entered into.

The mixer above referred to comprises a cylindrical shell *d* having an annular flange *e* by means of which the mixer is supported with the shell *d* within and in axial alignment with the duct through which the explosive mixture is conveyed to the engine. 15 The diameter of the shell *d* is preferably slightly less than that of the duct in which it is adapted to be supported and is of a length considerably less than the length of the shell of the agitator. Carried by the 20 shell *d* is the angular cross-bar *f* projecting from the shell *d* in the direction of the flow of the mixture. At the other end of the shell *d* is a cross-bar *g*, the said bars *f*—*g* being provided with suitable alined bearings for 25 the shaft of the agitator. Both of these bars may be secured to the shell *d* in any desired manner, as by means of ordinary screws, and movement of said bars prevented by soldering said bars to the said shell after they 30 have been properly trued up with relation to each other.

Mounted in the bearings upon the shafts *f*—*g* is the agitator shaft *h* which shaft has firmly secured thereto, so as to be rotatable 35 therewith, the helical strand *i*, the helices of which are of gradually increased diameter from adjacent opposite ends of said shaft to substantially the center of said helix. By making the said agitator *i* of a continuous 40 strand of round wire, retardation of the flow of the explosive mixture therethrough is reduced to a minimum, while sufficient resistance to said flow is offered to cause the rapid rotation of the agitator. The shaft *h* is 45 preferably mounted by means of ball-bearings in order to permit the shaft to turn freely and make the agitator sufficiently sensitive to be responsive to the slight energy exerted thereon by the flow of the gases. 50 The helix *i* at its greatest diameter extends into fairly close juxtaposition to the shell *d* and the various graduated helices comprised in said agitator are spaced apart sufficiently (axially of the shaft *h*) and are of graduated 55 diameters, so as to prevent the direct flow of the mixture therethrough while at the same time afford sufficient clearance between succeeding helices to avoid any substantial retardation of the flow of the mixture while causing such a diversion of separate portions thereof, as to assist materially in securing a thorough admixture of the component parts thereof.

I have found that a mixer embodying an 60 agitator such as that immediately above de-

scribed has high efficiency, but that by reason of a tendency of the agitator not to come to speed instantly toward the initiation of the suction stroke of an engine piston, that there is a very substantial loss of efficiency. 70 To obviate this difficulty, I provide in conjunction with said agitator, supplemental vanes which will have the effect of causing the agitator to come to speed substantially simultaneously with the initial development 75 of the suction at the agitator resulting from the suction stroke of the engine piston; to maintain this speed or even to insure an acceleration from the initial speed during the continuance of this suction stroke. By the 80 use of such supplemental vanes, I have found that the efficiency of the mixer may be almost doubled; which probably results from the increased speed of rotation of the agitator, with a resultant more thorough 85 commingling of the component parts of the mixture, and increase of the percentage of the mixture subjected to the action of the agitator during the suction stroke of an engine piston. In the practice of my invention the supplemental vanes referred to comprise four propeller blades *j*, *j'*, *j²*, and *j³*, of high pitch, mounted to have rotation with the shaft *h* and set at 90° apart. These blades are mounted within the helix *i* and 90 the edges thereof are made to conform with said helix in a manner to prevent the springing of the different helices of said helix and at the same time to avoid interference of the lateral flow of the mixture through the interstices between succeeding helices. Preferably I make the edges of the blades *j* to *j³* angular forming a series of seats for different points of the strand of the agitator *i*; and hold said strand firmly upon the seats 105 so formed by using the connecting stay wires *k* looped about each helix of the agitator and secured in place thereon. These tie strands also assist in securing a more thorough agitation of the mixture. By the arrangement of the plates *j* to *j³* shown and described, a sufficient resistance is offered to the mixture flowing through the agitator to insure a quick starting of the rotary movement thereof and the rapid development of 110 the maximum speed of the agitator. By the use of supplemental vanes the maximum speed of rotation of the agitator, over the old form, is materially increased and considering the quick response of the agitator to 115 the initial flowing of the gases a much higher average speed during each suction stroke is insured.

The shell *d* being somewhat constricted as compared with the duct or the aperture 120 in which it is inserted, the mixture, after passing through said shell, will have a tendency to expand. In order to secure the advantages of the accelerated flow adjacent the agitator, and at the same time take ad- 125

vantage of this expansion of the mixture, at least the forward end of the agitator is projected beyond the shell *d* and into that space in which the expansion of the mixture occurs. This construction permits a change in the direction of the flow of the mixture while still within the operative range of the agitator and thus permits the application of the mixer in a relation adjacent an elbow or 10 in an engine port.

In actual practice the agitator, upon the initiation of the engine suction stroke, is instantly rotated with rapidly increased velocity. The arrangement of the helix *i*, 15 blades *j* to *j'* and stay wires *k* is such as to insure this higher speed of rotation without at the same time presenting any substantial obstruction in the duct which would result in a retardation in the rate of flow of the 20 mixture. Not only will this agitator and its appurtenances constantly intercept and divert the moving gases but the centrifugal force developed by the high velocity of rotation will project any globules of hydrocarbon, toward the walls of the duct, and thus 25 tend to disrupt the same and cause them to combine with the air passing through said duct in the form of hydrocarbon spray. By reason of this action of the agitator, I am 30 enabled to throttle down the spraying valve to a point where the consumption of hydrocarbon, to a given engine speed, will be materially reduced from that required by an engine when not using the mixer. By 35 actual practice, I have demonstrated that with a carbureter so set as to cause an engine to readily start when a mixer made in accordance with my invention is used, the removal of the mixer will stall the engine, 40 or prevent its being started from the carbureter unless the spraying valve of the carbureter is adjusted to increase the volume of the hydrocarbon delivered thereby. I have also determined by actual tests that a 45 mixer equipped with supplemental vanes of a higher pitch than the strands of the agitator as herein described will readily start with the spray nozzle throttled down to a point at which the engine will not start 50 with a mixer in which such supplemental vanes are omitted.

It is not my intention to limit my invention, considered in its broader aspects, to the precise details of construction shown in the 55 accompanying drawings, it being apparent that these are largely matters of design and will of necessity vary with manifolds of different diameters or according to the design of the manifold or of the engine in connection with which the mixer is desired for 60 use.

Having described my invention, what I claim as new and desire to have protected by Letters Patent is:

65 1. An auxiliary gaseous fuel mixer em-

bodying therein a cylindrical shell provided with bearings at the opposite ends thereof, a rotatable shaft extending axially of said shell and mounted in said bearings, a helical agitator carried by and rotatable with said shaft, the helices of said agitator being spaced away from and apart axially of said shaft and of different diameters, and supplemental vanes of a different pitch from 75 said helices mounted upon said shaft within said agitator whereby the initial flow of the gaseous mixture will cause a substantially instantaneous rotary movement of said shaft.

2. An auxiliary gaseous fuel mixer embodying therein a cylindrical shell provided with bearings at the opposite ends thereof, a rotatable shaft extending axially of said shell and mounted in said bearings, a helical agitator carried by and rotatable with said 80 shaft, the helices of said agitator being spaced away from and apart axially of said shaft and of different diameters, and four propeller blades of high pitch mounted upon said shaft within said agitator whereby 85 the initial flow of the gaseous mixture will cause a substantially instantaneous rotary movement of said shaft.

3. An auxiliary gaseous fuel mixer embodying therein a cylindrical shell provided with bearings at the opposite ends thereof, a rotatable shaft extending axially of said shell and mounted in said bearings, a helical agitator carried by and rotatable with said 95 shaft, the helices of said agitator being spaced away from, and apart axially of, said shaft and of different diameters, and four propeller blades of high pitch mounted upon said shaft and extending substantially radially thereof, the outer edges of each 100 blade conforming to and extending into engagement with the helices of said agitator whereby the initial flow of the gaseous mixture will cause a substantially instantaneous 105 rotary movement of said shaft.

4. An auxiliary gaseous fuel mixer embodying therein a cylindrical shell provided with bearings at the opposite ends thereof, a rotatable shaft extending axially of said shell and mounted in said bearings, a helical agitator carried by and rotatable with 110 said shaft, the helices of said agitator being spaced away from, and apart axially of, said shaft and of different diameters, four propeller blades of high pitch mounted upon 115 said shaft and extending substantially radially thereof, the outer edges of each blade conforming to and extending into engagement with the helices of said agitator whereby the initial flow of the gaseous mixture 120 will cause a substantially instantaneous rotary movement of said shaft and stay wires secured to each helix and extending from one helix to the adjacent helices whereby 125 said helices are held against displacement 130.

with relation to said blades and agitating elements adjacent the shell are provided.

5. An auxiliary gaseous fuel mixer embodying therein a cylindrical shell provided with bearings at the opposite ends thereof, a rotatable shaft extending axially of said shell and mounted in said bearings, a helical agitator carried by and rotatable with said shaft, the helices of said agitator being 10 spaced away from, and apart axially of, said shaft and of different diameters, four propeller blades of high pitch mounted upon said shaft and extending substantially radially thereof, the outer edges of each blade 15 being angular to form seats for the helices of said agitator whereby the initial flow of the gaseous mixture will cause a substantially instantaneous rotary movement of said shaft and stay wires secured to each 20 helix and extending from one helix to the adjacent helices whereby the said helices are held against displacement with relation to said blades and agitating elements adjacent the shell are provided.
- 25 6. An auxiliary gaseous fuel mixer embodying therein a cylindrical shell provided with bearings at the opposite ends thereof, a rotatable shaft extending axially of said shell and mounted in said bearings, a helical agitator comprising a continuous strand of wire formed into a sequence of helices of 30 different diameter carried by and rotatable with said shaft, the helices of said agitator

being spaced away from, and apart axially of, said shaft and four propeller blades of 35 high pitch mounted upon said shaft and extending substantially radially thereof, the outer edges of each blade conforming to and extending into engagement with the helices of said agitator whereby the initial flow of 40 the gaseous mixture will cause a substantially instantaneous rotary movement of said shaft.

7. An auxiliary gaseous fuel mixer embodying therein a rotatable agitator comprising a plurality of concentric elements arranged one within the other, the outer element consisting of a continuous strand of helically wound wire, succeeding helices being 45 spaced apart axially of said agitator, and away from the axis thereof, and of different diameters, whereby a gaseous mixture can flow axially or radially of said agitator, and the inner element presenting surfaces of high pitch axially thereof whereby the 50 initial flow of the gaseous mixture will cause a substantially instantaneous rotary movement of said agitator and accelerate the speed of rotation thereof.

In witness whereof I hereunto affix my 60 signature in the presence of two subscribing witnesses this 16th day of March, 1914.

CHARLES SCHLAYER.
